UNITED STATES PATENT OFFICE.

JOSEPH K. ANDREWS, OF ANTRIM, OHIO.

COMBINATION OF SEAT AND CANE.

Specification of Letters Patent No. 26,643, dated January 3, 1860.

To all whom it may concern:

Be it known that I, J. K. ANDREWS, of Antrim, county of Guernsey, and State of Ohio, have invented a new and Improved 5 Cane Seat; and I do hereby declare that the following is a full and exact description thereof, reference being had to the accompanying drawings and to the letters of reference marked thereon.

10 In the drawings similar characters refer to like parts.

Figure 1 is a view of the cane as it appears when used as a walking-cane. Fig. 2 represents the cane when used as a seat. 15 Fig. 3 represents the cane when closed, the cap and ferrule being removed. Fig. 4 is the cap. Fig. 5 is the ferrule. Fig. 6 is the three pointed center-pin.

To enable others skilled in the art to make 20 and use my invention I will describe its construction and operation.

a represents the legs into which the main body of the cane divides when used as a seat. *b*, the three pointed center pin upon which 25 the legs of the cane work. *c* the canvas seat. *d* a pin fastened from the center of the under side of the seat. *e* the hollow cap which gives a finish to the cane, and conceals the seat. *f* the ferrule. *g* a spring for holding fast the ferrule. It will be seen by 30 the drawings that each of the legs is the third part of a cylinder, and that when

folded up they form a cylinder, which may be tapered off into a conical form like that of an ordinary cane.

In operating my invention I remove the ferrule *f* by pressing on spring *g*; I then remove cap or head *e*; then taking hold one end of the cane I separate the legs *a* which spreads open the canvas or leather seat, and 40 the invention is ready for use as a seat.

In folding it up so as to be carried conveniently, the seat *c* is folded up around the pin *d*, the lower end of which rests upon the upper ends of legs *a*, by this arrangement I can readily force the hollow cap *e* over the canvas seat and screw it on to the legs *a*.

Thus it will be seen that by a very simple and effective arrangement, I produce a cane 50 scarcely differing in any outward appearance from an ordinary cane, and yet one which can very readily be transformed into a convenient comfortable seat.

Having thus described my invention, what 55 I claim as new and desire to secure by Letters Patent is:

The cane is constructed for the purposes of a cane and seat, operating as described and for the purposes set forth.

J. K. ANDREWS.
